US0D1064166S

(12) **United States Design Patent** (10) **Patent No.:** **US D1,064,166 S**
(45) **Date of Patent:** **** Feb. 25, 2025**

(54) **OPTICAL SIGHT**

(71) Applicant: **Raytheon Canada Ltd.**, Ottawa (CA)

(72) Inventors: **John Maxwell Connolly**,
Penetanguishene (CA); **Carter K. McCormick**, Midland (CA)

(73) Assignee: **Raytheon Canada Ltd.**, Ottawa (CA)

(**) Term: **15 Years**

(21) Appl. No.: **29/895,217**

(22) Filed: **Jun. 19, 2023**

(51) LOC (15) Cl. **22-01**

(52) U.S. Cl.

USPC **D22/109**

CLAIM

The ornamental design for an optical sight as shown and described.

DESCRIPTION

FIG. 1 is a top view of a first optical sight according to this disclosure;

FIG. 2 is a side view thereof;

FIG. 3 is an opposite side view thereof;

FIG. 4 is a bottom view thereof;

FIG. 5 is an end view thereof;

FIG. 6 is an opposite end view thereof;

FIG. 7 is a top perspective view thereof; and

FIG. 8 is a bottom perspective view thereof.

FIG. 9 is a top view of a second optical sight according to this disclosure;

FIG. 10 is a side view thereof;

FIG. 11 is an opposite side view thereof;

FIG. 12 is a bottom view thereof;

FIG. 13 is an end view thereof;

FIG. 14 is an opposite end view thereof;

FIG. 15 is a top perspective view thereof; and,

FIG. 16 is a bottom perspective view thereof.

Mirror images of the optical sights are within the scope of the claimed design.

Broken lines in the drawings show environmental or optional structures and form no part of the design to be patented.

1 Claim, 14 Drawing Sheets
